UNITED STATES PATENT OFFICE

115,383

DESIGN FOR A ROLLING ASHTRAY

Edgar H. Barbe, Plainfield, N. J.

Application January 5, 1939, Serial No. 82,165

Term of patent 3½ years

To all whom it may concern:

Be it known that I, Edgar H. Barbe, a citizen of the United States, residing at Plainfield, county of Union, State of New Jersey, have invented a new, original, and ornamental Design for a Rolling Ashtray, of which the following is a specification, reference being had to the accompanying drawing, forming part thereof.

Figure 1 is a view in vertical elevation of a rolling ash tray showing my new design.

Fig. 2 is a side view in elevation showing my new design.

I claim:

The ornamental design for a rolling ashtray, as shown.

EDGAR H. BARBE.
